MILK BOTTLE SAFE

August A. Baum, New York, N. Y.

Application July 18, 1935, Serial No. 32,034

3 Claims. (Cl. 232—42)

One object of this invention is the provision of a receptacle or safe adapted to have one or more bottles of milk deposited therein by the milkman, the safe being so constructed as to prevent removal of the bottle through the opening by means of which it was inserted.

Another object of the invention is the provision of a milk bottle safe having means whereby the bottle may be removed through a door which can be opened only by the tenant of the house.

A further object of the invention is the provision of a milk bottle safe adapted to have one or more bottles inserted therein from the top of the safe, means being provided to prevent extraction of the bottle through the top once it has been inserted, the back of the safe having a door thereon through which the bottle may be extracted by its owner, the back of the safe standing against the door of the house so that access to the back door of the safe can be had only by first opening the house door, thus preventing unauthorized persons from gaining access to the milk bottles within the safe.

The above and other objects will become apparent in the description below, in which characters of reference refer to like-named parts in the accompanying drawing, forming a part hereof.

Referring briefly to the drawing, Figure 1 is a plan view, partly in section, showing the safe standing against the house door.

Figure 2 is a cross-sectional view taken on the line 2—2 of Figure 1.

Figure 3 is a reduced rear elevational view of the safe, partly in section, showing the back door lock in closed position.

Figure 4 is a fragmentary view similar to Figure 3, showing the back door lock in released position.

Referring in detail to the drawing, the numeral 10 represents the front wall of the safe or receptacle 11 having the rear wall 12. An opening 13 is provided in the top of the safe 11, which is normally closed by a pair of complementary doors 14 and 15 which are hingedly attached at 16 to the periphery of the opening 13, and which are normally urged into closed position by the spring 17. These doors can be swung downward through an arc of approximately 90 degrees, and when released are restored to their normal closed position.

Adjacent the front and rear walls of the safe, at a distance below the hinges 16, a pair of rods or shafts 18 are supported in the end walls of the safe. Rotatably mounted on each of these

shafts are a plurality of fingers 19 normally retained in horizontal or raised position by coiled springs 20 stretched between the said end walls. An ear 21 on each finger 19 acts as a limit stop to prevent the fingers from rising above the horizontal position. Each finger 19 comprises a U-shaped body having a pair of parallel walls 22 united by a web 23, the walls 22 projecting beyond the length of the web and being narrowed or tapered at their ends.

When a bottle is inserted through the top of the safe, the doors 14 and 15 will be forced downward into the position shown in broken lines in Figure 2. The bottle in its descent will then press the fingers 19 downward as shown in broken lines in Figure 2, and when the bottle has passed between the turned down fingers 19 the latter will rise to normal horizontal position. To permit the bottle to be dropped into the safe, the bottom is provided with a padded or raised resilient floor 24. Once the bottle is in the safe, there is little possibility that it can be removed through the opening 13.

The wall 12 is provided with an opening normally covered by a hinged door 25, the sides of this opening being formed by a frame formed integral with the end walls of the safe. A round hole is provided centrally through the door 25, through which a square stem 27 passes. This stem has an enlarged flat head 28 on the outside of the door, and its inner end is threaded to receive a lock nut 29. An extension lever or handle 30 has one end provided with a square hole through which the stem 27 passes, this lever end being clamped between the head 28 and the door 25 by means of the nut 29. The other end of the lever 30 is bent into a coil 31 around a resilient core 32. The house door is shown at 33, having the back of the safe 11 thereagainst when the door 33 is closed. The edge of the door 33 is beveled for a short distance at 35, so that when the door is closed the coiled end 31 of the lever 30 will lie in the space between the bevel 35 and the door jam 34, and be securely locked therein.

Between the nut 29 and the door 25, a locking cam 36, having therein a central square hole through which the stem 27 passes, is clamped. This cam 36 is substantially rectangular in shape and is provided with protruding rounded tongues 37 at opposite ends. When the cam 36 is in the position shown in Figure 3, the tongues 37 protrude over the frame 26 (as also shown in Figure 1), so that the door 25 cannot be opened. When the lever 30 is rotated counterclockwise to the vertical position shown in Figure 4, the tongues 37

37 will be clear of the frame 26, thus permitting the door 25 to be swung upward, whence the bottle may be removed from the safe. This can obviously not be done, however, while the house door 33 is closed.

Modifications in form and structure may be made without departing from the spirit and scope of the invention.

I claim:

10 1. A milk bottle safe comprising a box-like casing having an opening at the top through which the bottle is to be inserted, complementary swing doors horizontally pivoted about said opening having resilient means normally retaining said doors in closed position, shafts mounted parallel with said pivots in opposite walls of said casing, fingers rotatably mounted in a row on each of said shafts and normally projecting horizontally toward the center of said casing, a coiled spring 15 suspended from said opposite walls beneath each row of said fingers and normally raising said fingers, limit stops on said fingers to prevent the same from being rotated by said springs above the horizontal position, a door in the rear wall of 20 the casing through which the bottle may be removed therefrom, and means for locking said rear door.

2. A milk bottle safe comprising a box-like casing having an opening at the top through which the bottle is to be inserted, complementary swing doors horizontally pivoted about said opening having resilient means normally retaining said doors in closed position, means mounted below said doors for preventing lifting of the bottle therethrough after the bottle has been dropped to the bottom of said casing, a door in the rear wall of said casing through which the bottle may 10 be removed, and rotatable locking means mounted on said rear door.

3. A milk bottle safe comprising a box-like casing having an opening at the top through which the bottle is to be inserted, means mounted adjacent said opening for preventing withdrawal of the bottom therethrough after it has been inserted, a door mounted in the rear wall of said casing through which said bottle may be withdrawn, rotatable locking means mounted on said 15 rear door, a lever extending from said locking means and having an enlarged end, said enlarged end being jammed between the house door and the door jam thereof to prevent rotation of said locking means to open said rear door. 20 25

AUGUST A. BAUM.
